United States Patent Office

Des. 178,153

Patented June 26, 1956

178,153

VENTURI FITTING

Johannes Spring, Cranston, R. I., assignor to Taco
Heaters, Incorporated, Cranston, R. I., a corporation
of New York

Application September 16, 1954, Serial No. 32,318

Term of patent 14 years

(Cl. D91—3)

Fig. 1 is a side elevational view of a venturi fitting showing my new design;

Fig. 2 is a plan view;

Fig. 3 is an end view from the left of Fig. 1; and

Fig. 4 is an end view from the right of Fig. 1.

I claim:

The ornamental design for a venturi fitting, substantially as shown.
